UNITED STATES PATENT OFFICE.

ROBERT H. ROSS, OF YARMOUTH, NOVA SCOTIA, CANADA, ASSIGNOR OF ONE-FOURTH
TO ARTHUR W. GARDNER, OF YARMOUTH, NOVA SCOTIA, CANADA.

BUCKLE.

1,313,210.

Specification of Letters Patent. Patented Aug. 12, 1919.

Application filed November 9, 1917. Serial No. 201,139.

To all whom it may concern:

Be it known that I, ROBERT H. Ross, a subject of the King of Great Britain, residing at Yarmouth, in the Province of Nova Scotia and Dominion of Canada, have invented certain new and useful Improvements in Buckles; and I do hereby declare the following to be a full, clear, and exact description of the invention, such as will enable others skilled in the art to which it appertains to make and use the same.

This invention relates to improvements in buckles. The object of this invention is to improve the construction of buckles so as to render them capable of receiving a strap or lace therein, which strap or lace will be held against movement when the buckle is tightened or fastened thereto.

A further object of this invention is to provide a buckle having a supporting housing in which is a pivoted latch member and a lace or strap adapted to pass through the housing and over one end of the pivoted latch member and be retained therein by the latch member and against accidental lateral movement in either direction.

A further object of this invention is to provide a buckle capable of being used in connection with trunk straps, braces, garters, belts or other forms of straps.

A still further object of this invention is to provide a buckle of this character, which will be simple, practical and comparatively inexpensive in construction and one that can be manufactured and sold at a low cost.

With these and other objects in view, the invention consists in novel combination and arrangement of parts hereinafter more fully described and set forth in the claims hereto appended.

In the drawings:

Figure 1 is a top plan view of a buckle made in accordance with my invention.

Fig. 2 is a vertical longitudinal sectional view of the same.

Fig. 3 is a perspective view of the pivoted latch member.

Fig. 4 is a perspective view of the supporting housing for the latch member.

Fig. 5 is a detail sectional view illustrating the manner in which the pivoted latch member is pivoted to the side walls of the supporting housing.

Like numerals of reference designate cor-

responding parts in all the figures of the drawing.

Referring to the drawing, the numeral 5 designates the supporting housing in its entirety and it is constructed of a single piece of metal or other material suitable for the purpose and comprises a base plate 6 having its opposite side edges bent upwardly at right angles thereto to provide the side flanges 7. The side flanges 7 taper downwardly at the upper edge intermediate the ends thereof toward the ends of the side flanges, as illustrated in Fig. 4. A bar 8 is formed integrally with the upper edge of each side flange at the end thereof and extends from one flange to the other to overlie the base plate 6. The side flanges 7 also have formed integrally with their upper edges at the highest point thereof the keeper bar 9 which extends from one flange to the other to overlie the base plate 6 as illustrated. The side flanges 7 are also each provided with an alined transverse opening 10 which is located directly under the lug or keeper bar 9, as clearly illustrated in Fig. 4 of the drawing. The side flanges are also provided against one of their ends with vertical slots 11 which are in direct alinement with each other, the purpose of which will be hereinafter more fully described.

A pivoted latch member 12 comprises a body 13 which is substantially rectangular in cross section and it has its opposite side edges bent downwardly and tapered to provide the side flanges 14 which are provided in their larger ends at the bottom edge thereof with alined transverse openings 15. The forward edge of the plate is bent upwardly as at 16 and tapered to provide the cutting edge which constitutes a latch. The rear end of the plate 13 has its opposite side edges extended laterally as at 18 to provide manipulating fingers. An inverted U-shaped yoke 19 has the terminals of its arms formed integrally with the opposite side edges of the plate 13 and adjacent to the manipulating fingers 18, the web of the yoke being located in spaced relation to the body 13 and in a plane slightly below the upper cutting edge 17 of the latch member 16.

The pivoted latch member 12 is positioned between the side walls or flanges 7 of the supporting housing, and the openings 15 are adapted to aline with the openings 10, thus

positioning the latch 16 under bars 8 and the keeper bar 9. An eyelet pivot 20 is secured in the openings 15 and 10 and the flanges 7 and 14, respectively, thus pivoting 5 the latch member 13 to the side flanges 7 of the supporting housing, as illustrated in Figs. 1 and 2 of the drawing. The manipulating fingers, which align with the slots 11, are adapted to project therethrough 10 when in operative position, thus positioning the tapered cutting edge 17 of the latch 16 in close proximity to the under side of the keeper bar 9.

In use, a strap designated A in the drawing is inserted under one bar 8 at one end of the supporting housing 5. It is then run up over the latch 16 and inserted under the bar 9 and extends outwardly through the outer bar 8 at the opposite end of the plate 20 supporting house.

It can be readily seen that by virtue of the bars 8 the strap is held taut normally holding the manipulating fingered end of the pivoted latch down. When it is desired 25 to release the strap it is only necessary to grasp the lugs or fingers 18 with the fore finger and thumb of the hand and lift upwardly on the same to swing the pivoted latch member on its pivot 20 and move the 30 latch 16 away from the under side of the bar 9, thus permitting the strap to be readily withdrawn from the supporting house.

It will be apparent that the device may be used for a shoe lace and be suitably attached 35 to a shoe in any manner suitable for the purpose so that the laces may be readily inserted through the housing in a manner described for the strap to be locked therein.

Having thus described my invention, 40 what I claim is:

1. A buckle comprising a base plate,

transversely extending bars supported by said base plate at each end thereof and in spaced relation to the same, a retaining bar supported by the base plate centrally thereof, 45 said retaining bar extending transversely of the base plate and being positioned above the end bars, and a latch member pivotally mounted intermediate its ends upon the base plate and provided at one end with a gripping element positioned beneath and closely adjacent said retaining bar and co-operating therewith to grip a strap inserted between said end bars and the base plate and passed between the retaining bar and said gripping 55 element.

2. A buckle comprising a supporting housing including a base plate, tapered side flanges formed integrally with the base plate, bars formed integrally with the upper 60 edge of the flanges of the base plate at each end thereof and overlying the base plate, a retaining bar formed integrally with the upper edge of the flanges centrally thereof, said flanges provided adjacent 65 one end with slots, a pivoted latch member secured to the side flanges of the supporting housing, and manipulating fingers formed integrally with one end of the latch member and arranged in the slots, said latch being 70 provided at its opposite end with a gripping element co-operating with said retaining bar to grip a strap inserted between the latch member and retaining bar and between the bars at the ends of the flanges and said base 75 plate.

In testimony whereof I affix my signature in presence of two witnesses.

ROBERT H. ROSS.
